Inventor:
James T. Sibley, Francis A. Hosack,
By their Attorney, Geo. W. Heath

UNITED STATES PATENT OFFICE.

JAMES T. SIBLEY AND FRANCIS A. HOSACK, OF NEW YORK, N. Y.

POCKETKNIFE, ETC.

Application filed January 9, 1923. Serial No. 611,668.

To all whom it may concern:

Be it known that we, JAMES T. SIBLEY, a citizen of the United States, and a resident of the borough of Manhattan, city, county, and State of New York, and FRANCIS A. HOSACK, a citizen of the United States, and a resident of the borough of Manhattan, city, county, and State of New York, have invented certain new and useful Improvement in Pocketknives, Etc., of which the following is a specification sufficient to enable those skilled in the art to which the invention appertains to utilize the same.

The essential features of our present improvements are applicable to clasp and pocket knives generally, and in fact to any and all knives having one or more blades foldable as related to the handle. One object of our invention is to facilitate the manipulation of the blades, both in opening and closing the same, by simple but effective means, whereby the blades are automatically and positively locked in either prescribed position; another object of the invention is to render the blades and operative parts interchangeable and replaceable, so that substitution may be made for broken or worn parts, and also so that a set or series of interchangeable blades of various kinds, and for different purposes, may be provided and used in conjunction with the handle. To this end, the invention consists in the specific construction and combination of parts and appurtenances herein described and claimed specifically, arranged to operate conjunctively, substantially in the manner and for the purpose hereinafter fully set forth.

In the accompanying drawings we exemplify the essential features of our invention in practical form as embodied in a two-blade pocket knife, although we do not limit ourselves thereto, since a single-blade knife may be thus equipped, and minor details may be resorted to without departing from the spirit and intent of our invention in this respect. Furthermore, certain figures of the drawings show the structure, and component parts thereof, on an enlarged scale, for convenience of illustration.

With this understanding,

Fig. 1, represents an elevation of either side of our knife, closed;

Fig. 2, is a front view of the knife; 55

Fig. 3, is a rear view of the knife;

Fig. 4, is an end view of the knife;

Fig. 5, is a central longitudinal sectional elevation, taken upon plane of line 5—5, Fig. 1; 60

Fig. 6, is an elevation of the knife, one cheek piece being removed, and the view showing both blades extended, one broken away in part;

Fig. 7, is a like view, with one blade 65 in medial position, at right angles to the handle;

Fig. 8, is an elevation of the inner face of one of the cheek pieces of the handle;

Fig. 9, is a central longitudinal section 70 taken upon plane of line 9—9, Fig. 8;

Fig. 10, is an elevation of the tang recessed side of a blade;

Fig. 11, is a transverse section through the tang of the blade, taken upon plane of line 75 11—11, Fig. 10;

Fig. 12, is a view like unto Fig. 10, showing a modification in the form of the tang recess;

Fig. 13, is a transverse section taken upon 80 plane of line 13—13, Fig. 12;

Fig. 14, is an elevation of the recessed side of one of the manipulative cam rings;

Fig. 15, is an edge elevation thereof, looking in the direction of the arrow 15, Fig. 14; 85

Fig. 16, is an elevation of the edge of the manipulative cam ring on the side opposite to that shown in Fig. 15;

Fig. 17, is an elevation of the side of manipulative cam ring opposite to that 90 shown in Fig. 14;

Fig. 18, is a side elevation of one of the latch springs;

Fig. 19, is an edge view thereof;

Fig. 20, is a detail view of one of the fulcrum studs; 95

Fig. 21, is a transverse section taken upon plane of line 21—21, Fig. 1, the blades being omitted.

The main parts of the handle H, may be designated for convenience of description, as the cheek pieces h' h^2 , which are duplicates in every respect, being each formed with a longitudinal spine flange h^x , so that

when reversed and superposed with relation to each other they constitute a unitary structure, with the blade channel h^3 , between them,—each spine flange h^x , forming one 5 half of the width of said blade channel.

The two cheek plates h' , h^2 , are held together near each extremity by fulcrum studs s , s , one end of each of which is screw threaded for engagement with a binding nut n , the other extremity of each fulcrum stud s , s , being rigidly attached to one 10 of the cheek pieces, as will be understood by reference more particularly to Fig. 5, of the drawings. Thus each cheek piece h' , h^2 , 15 has fixedly secured to it one of said fulcrum studs s , s , and each is recessed to form a countersink h^4 , for the accommodation of one of the binding nuts n , n . The medial portion s' , s' , of each fulcrum stud s , s , is 20 of greater diameter than the end portions thereof, forming shoulders s^2 , s^2 , (Fig. 20), which supplement the spine flange h^x , in spacing the cheek pieces h , h , apart.

Each cheek plate h , is formed on its inner 25 side with a longitudinal recess h^5 , for the accommodation of a latch spring l , countersunk therein, as shown more particularly in Figs. 5 and 21, of the drawings, the reversal of the cheek plates h' , h^2 as related 30 to each other as before stated positioning these recesses, h^5 , and their latch springs l , in alignment on opposite extremities of the knife handle. The shanks of the latch springs l , may be secured in position by 35 screws l' , centrally positioned in the cheek plates, as shown or otherwise rigidly attached, to the cheek plates h' , h^2 , the free ends of said latch springs l , being formed with lateral shoulders l^x , for the purpose 40 hereinafter set forth. Concentric with the axes of the fulcrum studs s , s , each end of each cheek plate h' , h^2 , is formed with a semi-circular stop groove h^6 , for the accommodation of stop studs b' , protuberant on 45 each side of the tang b , of each blade B. The said concentric semi-circular grooves h^6 , in the cheek pieces, are positioned at the ends 50 of the latter, or in other words, beyond the axes of the fulcrum studs s , s , as shown more particularly in Fig. 8, of the drawings, the contacting of said tang stop studs b' , with the ends of the said concentric stop 55 grooves h^6 , limiting the extent of movement of the blades B, in either direction. That is to say, the semi-circular stop grooves h^6 , admit of a one half turn of each blade on its fulcrum (i. e. the medial portion s^2 , of its stud s) while prescribing the longitudinal alignment of the blade B, in either direction 60 as related to the handle H.

Each blade is held in extended or retracted position, as the case may be, by the engagement of a spring latch shoulder l^x , with a diagonal groove b^2 , in its tang b , 65 said spring latch shoulder l^x , being actuated

and controlled by means of a cam ring K, formed with cam surfaces k' , k^2 , adapted to lift the latch shoulder l^x , out of said diagonal groove b^2 , upon occasion, against the resistance of the spring l , which latter tends 70 constantly to maintain engagement with the cam ring K, and blade tang b .

The rotative cam rings K, are mounted between the ends of the cheek plates h , h , on the annular shoulders h^4 , h^4 , which are 75 concentric with the fulcrum studs. They are each formed with a blade recess h^3 , the end shoulders of which contact with the tang b , of the blade. Hence, as the blade B, is limited to a half turn by the protrusion of its stop studs b' , b' , into the semi-circular stop grooves h^6 , of the cheek plates 80 h' , h^2 , it is obvious that the limitation of motion of said cam ring K, will be one half 85 a rotation.

The peripheral surface of each cam ring K, where exposed at the end of the handle, is knurled, or otherwise roughened as at 90 h^x , to facilitate manipulation by finger contact.

In operation, the pressure of the finger, or fingers, on the said knurled peripheral surface of a cam ring K, effects the partial rotation thereof, causing one or the other cam surface k' , or k^2 , as the case may be, to lifting 95 the latch shoulder l^x , out of the diagonal groove b^2 , in the tang b , of the blade, so that the latter, with the cam ring K, may be turned a one half revolution, at the completion of which the latch shoulder l^x , automatically re-engages the diagonal tang 100 groove b^2 , thereby locking the blade in the prescribed position, either extended in alignment with the handle, or retracted therein.

The side walls of the diagonal groove b^2 , 105 of the tang b , may be either rectangular, as shown more particularly in Figs. 10 and 11, or may be slightly bevelled, as indicated in Figs. 12 and 13, of the drawings, in which latter case the spring latch will yield in 110 the event of excessive pressure on the back of the blade when open, and thereby prevent fracture of any of the parts involved.

The nuts n , may be nicked for engagement with a key by which they may be 115 tightened or loosened in position upon the screw ends of the fulcrum studs.

The removal of said nuts n , admits of the separation of the parts, so that changes or replacements thereof may be readily effected.

What we claim as our invention and desire to secure by Letters Patent is,

1. In a knife of the character designated, 125 the combination of duplicate cheek plates, one of which is formed with a spine flange and with a screw threaded fulcrum stud, and with semi-circular stop grooves concentric with said fulcrum stud, and also with an annular shoulder concentric thereto, 130

- a blade pivotally mounted on said fulcrum stud and formed with a tang stop stud protruding into said semi-circular groove in the cheek plates and also formed each with a 5 diagonal tang groove, a spring latch engaging with said diagonal tang groove, a cam ring rotatively mounted on said concentric shoulder on one of the cheek plates and engaging with said spring latch, and a nut 10 engaging the threaded end of said fulcrum stud, substantially in the manner and for the purpose set forth.
2. In a knife of the character designated, the combination of spined cheek plates, ful- 15 crum stud connecting said cheek plates, each cheek plate being formed with semi-circular stop grooves concentric with said fulcrum studs and also with annular shoulders concentric thereto, said cheek plates 20 being likewise formed with longitudinal recesses on their inner faces for the accommodation of a spring latch, said spring latches, a blade pivotally mounted on said fulcrum stud and formed with tang a stop 25 stud protruding into the said semi-circular grooves in the cheek plates and also formed each with a diagonal tang groove for engagement with said spring latch, a cam ring rotatably mounted on said con-
- centric annular shoulders on the cheek 30 plates, and a nut countersunk in the cheek plates and engaging the threaded end of said fulcrum stud, substantially in the manner and for the purpose described.
3. In a knife of the character designated, 35 the combination of spined cheek plates, a fulcrum stud connecting said cheek plates, each cheek plate being formed with semi-circular stop grooves concentric with said fulcrum stud and also with an annular 40 shoulder concentric thereto, a blade pivotally mounted on said fulcrum stud and formed with tang stop studs, projecting into said semi-circular stop grooves in the cheek plates and also formed with a diagonal tang 45 groove, a spring latch engaging with said diagonal tang groove, a cam ring rotatively mounted on said concentric annular shoulders on the cheek plates, and a nut engaging the threaded end of said fulcrum stud, 50 for the purpose, and substantially in the manner set forth.

JAMES T. SIBLEY.
